MINING AND LOADING MACHINE WITH UPPER AND LOWER RELATIVELY MOVABLE DISINTEGRATING HEAD PORTIONS

Charles F. Ball, Franklin, Pa., assignor to Joy Manufacturing Company, Pittsburgh, Pa., a corporation of Pennsylvania

Application September 15, 1951, Serial No. 246,776

52 Claims. (Cl. 262—9)

This invention relates to a mining and loading apparatus and more particularly to a mining and loading apparatus for disintegrating the mineral of a solid mine vein and for gathering and loading the disintegrated mineral whereby production of mineral may be effected in a substantially continuous manner.

In the continuous mining of mineral, such as coal, from a solid seam or vein, it has heretofore been common practice to employ a rotary boring head embodying a plurality of coating rotary boring instruments for disintegrating the solid vein, and such known types of apparatus are relatively inflexible and usually operate along a substantially rectilinear path to effect the formation of straight passageways or entries. While, in known instances, such apparatus are capable of making wide lateral turns, they are relatively unwieldy and cumbersome in operation, and the conveying means is necessarily relatively wide in order to obtain the desired loading efficiency. Also, such known types of apparatus lack the desired readiness of control and flexibility in vertical adjustment, preventing the machine from readily following an uneven or rolling seam as mining progresses and the machine is advanced. Further, such known types of rotary boring head machines, due to their particular design, present space restrictions whereby relatively free flow of the disintegrated mineral to the conveying means of the machine is prevented thereby impeding operation of the machine. The present invention contemplates improvements over such known rotary boring head types of apparatus in that extreme flexibility in adjustment, both vertically and laterally, is provided. Moreover, relatively wide flow spaces or openings are provided through which the disintegrated mineral may flow toward the conveying means of the apparatus thereby facilitating movement of the disintegrated mineral toward the conveying means and greatly improving the operating efficiency of the machine as well as reducing clogging and increasing the lump size obtainable. Furthermore, in order to attain the desired flexibility, a narrow conveying means must be provided, and with such a narrow conveying means it is necessary to provide auxiliary conveying means associated with the relatively wide disintegrating head mechanism for moving the disintegrated mineral received within the head laterally onto the conveying means. The apparatus of the present invention is relatively compact, is relatively rugged in design and has relatively great flexibility, well adapted for its intended purpose.

An object of the present invention is to provide an improved mining and loading apparatus whereby mineral such as coal may be mined in a substantially continuous manner from a solid vein and rapidly gathered and loaded into the conventional haulage means of the mine. Another object is to provide an improved continuous miner whereby the mineral of a mine vein may be rapidly mined and loaded out with the necessity of only a few positioning movements of the apparatus during its operation. A further object is to provide an improved continuous

2

miner of the rotary boring head type having improved adjustable supporting structure for the boring head whereby the latter may be readily adjusted laterally with respect to the base of the machine and embodying in the head, improved adjustable means whereby the machine may operate on mine veins of widely varying heights. A further object is to provide an improved continuous miner having an improved disintegrating head, improved conveying means, and improved gathering and collecting means whereby the disintegrated mineral may be rapidly gathered and collected within the machine and moved onto the conveying means. A further object is to provide an improved disintegrating head mechanism providing a relatively large zone of accumulation for the disintegrated mineral within the head together with improved means for moving the mineral accumulated within the head onto the conveying means. A still further object is to provide an improved disintegrating mechanism for a continuous miner whereby a lower disintegrating head portion cooperates with an upper disintegrating head portion and wherein improved means is provided for rapidly moving the upper disintegrating head portion relative to the lower head portion during the disintegrating operation. Still another object is to provide an improved adjustable means associated with the moving means for the upper head portion whereby mine veins of widely varying heights may be disintegrated. A further object is to provide an improved adjustable disintegrating head structure whereby the latter may readily follow a rolling or uneven seam or vein. Still another object is to provide an improved disintegrating mechanism embodying a lower boring head portion and an upper cutting portion, together with improved means for adjusting the upper cutting portion in a vertical direction relative to the lower boring head portion to vary the operating height of the mechanism. A further object is to provide an improved disintegrating head mechanism for a continuous miner embodying mineral disintegrating mechanism and improved driving means for the disintegrating mechanism. Yet another object is to provide an improved continuous miner of the rotary boring head type having improved supporting and adjusting means for the boring head whereby the range of operation of the machine is greatly increased. These and other objects and advantages of the invention will, however, hereinafter more fully appear in the course of the ensuing description.

In the accompanying drawings there is shown for purposes of illustration one form which the invention may assume in practice.

In these drawings:

The mining and loading apparatus of the present invention constitutes an improvement over that disclosed in my copending application, Serial Number 191,004, filed October 19, 1950, now abandoned and which has been replaced by continuation application Serial Number 594,339, filed June 21, 1956 in that an improved disintegrating mechanism together with improved gathering and collecting means for the disintegrated mineral are provided within the machine whereby the mineral of a solid mine vein may be efficiently and rapidly mined and loaded out in a substantially continuous manner.

The mining and loading apparatus disclosed herein generally comprises a mobile base generally designated 1 having a horizontal swingable supporting structure 2 pivotally mounted thereon and the frame structure carrying a vertically swingable support 3 for a disintegrating head mechanism generally designated 4. The disintegrating head mechanism embodies a lower boring head portion 5 and an upper adjustable cutting head portion 6 which desirably has vertical operating movement relative to the lower head portion during the disintegrating operation. Rotary gatherers 7 cooperate with rotary conveyor devices 8 for gathering and collecting the disintegrated mineral within the head mechanism and for moving the mineral so collected onto a front conveying means, generally designated 9, of the machine. Motors 10 and 11 are mounted on the horizontally swingable supporting structure 2 at its opposite sides and one motor serves to drive the upper cutter head portion 6 while the other motor serves to drive the other lower boring head portion 5, the rotary gatherers 7, the rotary conveyor devices 8 and the conveying means 9. A conventional, independently driven, rearward conveying means 12 cooperates with the conveying means 9 in the moving of the disintegrated mineral rearwardly away from the face of the mine vein to a convenient point of delivery at the rear end of the machine to the conventional mine haulage means. The disintegrating head mechanism 4 is mounted on the vertically swingable support 3 for rectilinear guided movement relative to the swingable frame structure and the base irrespective of the horizontally swung position of the swingable supporting structure relative to the base, whereby the disintegrating head mechanism may be thrust forwardly into the mineral of the vein and may be retracted from the vein during the disintegrating operation regardless of the angular position of adjustment of the swingable supporting structure thus enabling a face of substantial width to be mined out.

Specifically, the mobile base 1 of the improved continuous miner constitutes a crawler tread device, although, evidently, the machine may be mounted on any suitable type of base structure. This crawler tread device may be similar to that disclosed in my copending application Serial Number 86,516, filed April 9, 1949,

now matured into Patent No. 2,705,626, dated April 5, 1955, and comprises a base frame 15 having side frames 16 providing guideways about which endless crawler tread chains 17 are guided for orbital circulation. These crawler tread chains may be driven by individual motors whereby the treads may be operated and controlled to effect propulsion and steering of the apparatus as it travels over the mine floor, both during tramping about the mine and positioning of the machine with respect to the mine face during the disintegrating operation. The horizontally swingable supporting structure 2 is mounted on and overlies the base frame with its forward portion overhanging the base frame and is pivoted at its rearward portion at 18 on an upright axis located at the rear end of the base frame. As shown in Fig. 7, a vertical pivot pin 18^a is rigidly secured to the base frame midway between the sides of the latter and is pivotally engaged by a bearing carried by the rearward portion of the swingable frame structure 2 thereby to provide such upright pivot 18. The frame structure 2 is guided by an arcuate guide member 19 on the base during its horizontal swinging movement about the pivot 18. The vertically tilttable support 3 comprises an elongated longitudinally extending frame 20 arranged intermediate the parallel side members 21 of the frame structure 2 and this tilttable support is pivoted at 22 (Fig. 2) on a horizontal transverse axis on the rearward portion of the swingable supporting structure 2 to tilt in a vertical direction relative to the latter. A pair of hydraulic jacks 23, shown in Figs. 1 and 6, operate between the swingable frame structure 2 and the tilttable support 3 for effecting tilting of the latter to vary the elevation of the disintegrating head mechanism 4, in a manner fully disclosed in my copending application, Serial Number 191,004, above referred to. Mounted at the sides of the horizontally swingable frame structure 2 are parallel, longitudinally extending, hydraulic jack cylinders 24 which have pulleys 25 carried by the forward ends of their piston rods and a pair of cable sections 26 are fastened at one end at 27 to the cylinders and pass around rearwardly located guide sheaves 28 carried by the frame structure near the rear ends of the jack cylinders, as shown in Fig. 2. These cable sections extend forwardly and inwardly, as indicated in dotted lines in Fig. 1, and pass around a pair of guide sheaves 29 on the swingable frame structure (see Figs. 1 and 5), and are fastened at their opposite ends at 30 to opposite ends of the guide member 19 at the outer sides of the base frame. Thus, as the pistons are moved within the jack cylinders the frame structure 2 may be swung horizontally with respect to the base in a manner generally similar to that disclosed in my copending application, Serial Number 191,004, mentioned above.

As shown in Fig. 7, the conveying means 9 is in the form of an endless flight conveyor having endless side drive chains 35 suitably guided for circulation within appropriate guideways on the tilttable support 3 and to which cross flights 36 are secured at spaced intervals, and the flights of the top run of the conveyor move along a bottom plate 37 so that the disintegrated mineral received by the conveyor, in a manner to be later explained, may be moved rearwardly along the tilttable frame to discharge onto the rearward conveyor means 12 which will be later referred to. The intermediate portion of the lower run of the conveyor passes around upper drive sprockets 38 and lower guide sprockets 39, as shown in Fig. 7, and the guide sprockets 39 are suitably guided for rectilinear movement and are urged rearwardly along their guides by coil springs 40 to apply the desired tension to the conveyor side chains. The forward portion of the conveyor passes around chain sprockets 41 secured to a cross shaft 42 suitably journaled within the lower frame portion of the disintegrating head mechanism, and the rearward portions of the conveyor chains pass around guide sprockets 43

secured to a cross shaft 44 (see Fig. 7) suitably journaled within the rearward portion of the tiltable support 3.

Now referring to the specific structure of the disintegrating head mechanism 4, it will be noted that the forward portion of the frame 20 of the tiltable support 3 carries a relatively wide transverse head frame portion 49 extending across the forward end of the machine and of a width greater than the rearwardly located parts of the supporting frame structure, as shown in Figs. 1 and 3. This frame has a bottom, forward, nose portion 50 engageable with the floor and providing a transverse penetrating edge disposed at the floor level. This transverse forward frame portion carries suitable bearing supports 51 in which are mounted suitably axially spaced bearings 52 in which parallel longitudinal shafts 53 are journaled (see Fig. 9) and secured, as by keys, to the forward end portions of these shafts are rotary boring instruments or devices 54 having hubs 55 formed with lateral arms 56 which carry appropriate cutting or disintegrating elements 57. The hubs of the boring instruments are retained axially in position on the shafts by nuts 58 threaded on the shaft-ends for holding the hubs rearwardly against spacing sleeves abutting the outer bearings, in the manner shown. Tubular housings 59 are secured to the front bearing supports of the head frame and are arranged to enclose the bearings and these carry suitable sealing rings 60 which engage the arm-hubs 55 to prevent entry of dirt to the bearings. Each longitudinal shaft is formed at its forward end with a conical recess or socket 61 which receives the conical shank of a central boring tool or bit 62 and these boring tools cooperate with the boring instruments 54 in the disintegration of the mineral. The tools 62 have lateral lugs 63 (Fig. 9) engaged in radial slots in flanges 64 integral with the hubs 55 of the boring instruments, so that the bits are interlocked with the boring instruments for rotation therewith.

The motors 10 and 11 are desirably electric motors and have their housings suitably supported at the outer sides of the longitudinal frame members 21 of the horizontally swingable frame structure 2, as shown in Fig. 5. These motors each has its power shaft connected to a speed reducer, as disclosed in my above-mentioned application, Serial No. 191,004. The motor 11 drives through its speed reducer a universal coupling 65 connected to a telescopic shafting 66 which is in turn connected through a universal coupling 67 to a longitudinally extending shaft 68 suitably journaled within a housing or gear box 69 carried at one side of the head frame (Fig. 9). This shaft 68 is suitably journaled in bearings supported within the gear box 69 and has fixed thereto a spur gear 70 which drives through an intermediate or reach spur gear 71, a spur gear 72 secured to a parallel shaft 73. Spur gear 71 is rotatable relative to and has its hub surrounding the coaxial boring-head-shaft 53, as shown. The gear 70 and the shaft 73 are likewise suitably journaled in bearings supported within the gear case 69 and secured to and driven by the shaft 73 is a bevel gear 74 meshing with and driven by a bevel gear 75 secured to a transverse shaft 76. This shaft extends transversely of the head frame and is suitably journaled in bearings supported within the gear box 69 and the inner end of this shaft is connected by a flexible coupling 76^a (see Fig. 10) to a cross shaft 76^b which extends transversely beneath the head frame (see also Figs. 6 and 7). This cross shaft is in turn connected by a flexible coupling 76^c to a transverse shaft 76^d suitably journaled in bearings supported within a housing or gear box 69^a carried at the opposite side of the head frame (see Figs. 1 and 10). The elements 76, 76^b and 76^d of the cross shafting revolve as a unit and this cross shafting has secured thereto, near its opposite ends, worms 77 having teeth of opposite pitch and arranged within the gear boxes 69 and 69^a. These worms respectively mesh with worm

wheels 78 having their hubs secured to the two parallel outer shafts 53 of the boring head. Secured to and driven by the two outer boring head shafts 53 respectively are spur gears 79 (see Fig. 11) which drive through intermeshing intermediate spur gears 80 and 81, spur gears 82 respectively secured to the two inner boring head shafts 53. These spur gear trains are arranged within gear chambers 83 formed in the head frame, in the manner shown. Thus, when the cross shafting is driven by the motor 11 through the spur and bevel gearings, the two outer boring instruments 54 rotate in relatively opposite directions while the two inner boring instruments concurrently rotate in relatively opposite directions which are opposite to the directions of rotation of the two outer boring instruments. Desirably, the first and third boring instruments 54, as viewed from left to right in Fig. 3, revolve in a counterclockwise direction, while the second and fourth boring instruments revolve in a clockwise direction.

Driven also by the shaft 68 (Fig. 9) is a chain sprocket 85 which is connected by an endless drive chain 86 (Fig. 10) to a chain sprocket 87 secured to a longitudinal shaft 88 suitably journaled at one side of the tiltable support 3, as shown in Fig. 1. This shaft is connected by a universal coupling 89 to a longitudinally extending shaft 90 which is in turn connected through a universal coupling 91 to a longitudinal shaft 92 (Fig. 5) suitably journaled within a gear housing 93 secured to the side of the tiltable support 3. Secured to this longitudinal shaft is a worm 94 meshing with a worm wheel 95 secured to a cross shaft 95^a to which the sprockets 38 which drive the front conveying means 9 are secured. Thus, during operation of the boring head the front conveying means 9 is concurrently driven.

As shown most clearly in Fig. 3 there is a relatively large space or opening 96 between the two inner boring instruments above the receiving end of the conveying means 9 and similar relatively large laterally located spaces or openings 97 and 98 are arranged intermediate the pairs of rotary boring instruments above the rotary gatherers 7. The rotary gatherers are each in the form of toothed drums 99 which are journaled within the head frame in transverse axial alignment with and are coupled to the cross shaft 42 of the conveying means 9. Thus, the rotary gathering drums are driven by the front cross shaft which is driven by the front conveyor. The teeth of these rotary gathering drums move through suitable slots formed in comb members 100 suitably mounted within the lower portion of the head frame so that as the disintegrated mineral is gathered by the rotary gatherers and moved rearwardly over the tops of the drums, the mineral is deflected from the drum teeth by these combs and the disintegrated mineral so deflected moves rearwardly into relatively large chambers 101 formed within the head frame rearwardly of the rotary boring instruments. The rotary conveyor devices 8 are arranged within these chambers, as shown in Fig. 4, and each comprises a rotary member or impeller having a hub 102 secured to a shaft 103 suitably journaled in bearings supported within the head frame, as shown in Fig. 6. These rotary impeller members have parallel longitudinal arms 104 and as the rotary members are driven they turn in relatively opposite directions in such manner as to cause the arms thereof to engage the disintegrated material received in the chambers 101 and move the disintegrated material laterally inwardly along the curved bottom walls 101^a of the chambers (Fig. 4) onto the conveying means 9.

Thus, it will be seen that the machine has a relatively large zone of accumulation within the head rearwardly of the rotary boring instruments so that the disintegrated mineral may flow, with the aid of the rotary gatherers 7, relatively freely through the large front openings into such zone of accumulation and the rotary conveyor devices 8 within the head engage the disintegrated mineral

accumulated within the head and move it laterally over the sides of the front conveyor 9. By the provision of the large openings across the lower portion of the head frame, the disintegrated mineral may flow relatively freely rearwardly into the head where it is received by the conveyor and the latter rapidly moves the mineral away from the head thereby substantially reducing the possibility of clogging. Moreover, by rapidly removing the disintegrated mineral from the operating zone of the boring instruments in the vicinity of the working face efficiency is greatly improved as well as resulting in an increase in the lump size of the mineral being loaded out. These rotary conveyor devices 8 are driven through chain sprockets 105 connected by conventional slip clutches 106 to the parallel outer shafts 53 of the boring head and these sprockets are connected through endless drive chains 107 to chain sprockets 108 secured to the shafts 103 of the rotary conveyor members. Thus, during the disintegrating operation the disintegrated mineral may move into the centrally located space or opening 96 directly onto the forward portion of the conveying means 9 and the disintegrated mineral at the sides of the head is engaged by the rotary gatherers 7 and is moved rearwardly through the side openings 97 and 98 into the chambers 101 where it is engaged by the rotary conveyor members 8 and moved laterally inwardly onto the conveying means 9 over the sides of the latter. Thus, relatively wide open flow spaces or openings which promote the free flow of the disintegrated mineral within the frame of the disintegrating head are provided, and as the boring instruments are rapidly rotated and the upper chain portion is operated to effect disintegration of the mineral, the disintegrated mineral is directed toward these open spaces. The lower head frame 49 has curved deflector portions 109 at its sides rearwardly of the side boring instruments, and these deflector portions substantially fit the side walls of the outer bores to prevent passage of the disintegrated mineral rearwardly of the head.

Now referring to the upper adjustable cutting head portion 6 of the disintegrating mechanism, it will be noted that the motor 10 has its power shaft connected through its speed reducer to a universal flexible coupling 110 connected to a telescopic shafting 111 which is in turn connected by a universal flexible coupling 112 to a longitudinal shaft 113 suitably journaled with a housing 114, as shown in Fig. 8. Secured to the shaft 113 is a spur gear 115 which meshes with a spur gear 116 secured to a parallel shaft 117 likewise suitably journaled within the gear housing. Secured to the shaft 117 is a spur pinion 118 meshing with a spur gear 119 secured to a parallel shaft 120 likewise suitably journaled within the gear housing. The shaft 120 projects forwardly from the gear housing and has secured to its projecting end a chain sprocket 121 which engages and drives an endless loop type, face cutter type cutter chain 122 having an elongated open center and guided for orbital circulation in a guideway 123 on an upper adjustable frame 124 by which the housing 114 is carried. At the end of the cutter frame opposite from that at which the drive sprocket 121 is located is a conventional chain idler sprocket 125 about which the cutter chain passes. This idler sprocket may be adjusted in a conventional manner relative to the cutter frame to vary the tension of the cutter chain. The links of this endless cutter chain carry suitable forwardly projecting cutting or disintegrating elements 126. As shown in Fig. 6, the upper cutter frame 124 is pivoted at 127 (see Fig. 6) on a horizontal transverse axis at its rearward end to swing in a vertical direction relative to the lower boring head frame and arranged between the boring head frame and the adjustable upper cutter frame are hydraulic jacks 128. These jacks comprise cylinders 129 pivotally mounted at 130 on the lower portion of the boring head frame and contain pistons 131 hav-

ing upwardly projecting piston rods pivotally connected at 132 to the upper portion of the cutter frame, as shown in Fig. 6, so that when fluid is properly supplied to these jack cylinders, the cutter frame may be swung up and down in a vertical direction as desired and by trapping liquid in the cylinders the cutter frame may be locked in adjusted position. As shown most clearly in Fig. 6, the cutter frame and the endless cutter chain carried thereby when in lowered position move downwardly with its lower portion disposed in a transverse space 133 between the forward portion of the head frame and the rear surfaces of the rotary boring instruments, in an extremely low compact manner. Evidently, the cutting means of the upper disintegrating portion 6 may assume other known forms and the form disclosed is merely exemplary for illustrative purposes.

The horizontally swingable frame structure 2 has parallel longitudinally extending guides 135 at the inner sides of the parallel side frame members 21, as shown in Fig. 5, 20 and the tiltable support 3 is mounted on members providing guideways in which these guides are received whereby the support 3 together with the disintegrating head mechanism 4 may be moved rectilinearly back and forth relative to the frame structure 2, also in a manner 25 similar to that disclosed in my copending application, Serial Number 191,004, mentioned above. It will be noted that the guides 135 of the frame structure 2 remain substantially horizontal irrespective of the tilted position of the support 3. For effecting such longitudinal adjustments of the head mechanism 4 there are provided longitudinally disposed hydraulic feeding jacks 136 having cylinders pivotally connected at their forward ends at 137 to brackets 138 rigidly secured to the inner sides of the frame side members 21, as shown in Fig. 1, and contained in these cylinders are pistons 139 having rearwardly 30 projecting piston rods 140 which are pivotally connected at 141 to guide members 142 slidably engaging the guides 135 on the swingable frame structure 2. The rearward portion of the tiltable support 3 carries stub shafts 143 35 (Fig. 1) which are pivotally mounted on the guide members 142 to provide the support pivot 22. Thus, when liquid under pressure is properly supplied to these jack cylinders, the support 3 together with the disintegrating head mechanism may be moved rectilinearly back and forth along the guides 135 relative to the frame structure 2, and by trapping liquid in these cylinders, the head mechanism may be held rigidly in adjusted position. These feed cylinders are employed to thrust the disintegrating head mechanism forwardly into the mine vein during the sumping operation and to retract the head mechanism from the vein, and the head mechanism may be moved back and forth rectilinearly along the support 3 irrespective of the tilted position of the head frame or the angular position of the frame structure 2.

50 The loop type face cutter chain 122 of the upper disintegrating portion 6, if held stationary as regard to vertical movement, as the disintegrating head mechanism is advanced toward the face, would form an attached core of mineral at its open center in an obvious manner and, therefore, it is advantageous to effect movement of the cutter chain up and down as it circulates in its orbit relative to the cutter frame during its cutting function so that the mineral above the rotary boring instruments may be completely dislodged and disintegrated. By causing the 55 cutter chain 122 to move bodily up and down as it travels its orbital path, the cutting elements 126 travel relative to the mineral in oblique paths—downwardly inclined, upwardly inclined, and consisting of portions, varying inversely in length, of each inclination—in a generally criss-cross pattern, whereby the mineral is dislodged in a most effective manner. Also, it is desirable to adjust the cutter chain vertically relative to the boring instruments so that seams or veins of widely varying heights may be 60 mined out. While, evidently, the elevating jacks 128 may be under manual control, it is desirable to render such up 65

and down movement of the cutter chain completely automatic irrespective of any given height of vertical adjustment. To accomplish this highly desirable function a pump 150 (Fig. 13), suitably driven by one of the motors 10 or 11, has its suction side connected by conduit 151 to a liquid tank 152 and the discharge side of the pump is connected by conduit 153 to a manual control valve device 154 containing a conventional slide valve 155 of the spool type. The discharge passage of this valve device is connected by a return conduit 156 back to the tank. The pressure passage of this valve device is connected by conduit 157 to an automatic control valve mechanism 158 and the usual discharge passage of this valve mechanism is connected by a return conduit 159 past a conventional check valve 160 to the return conduit 156 leading back to the tank. The usual pressure passages of this valve mechanism are connected by pairs of conduits 161 and 162 to the opposite ends of the elevating jack cylinders. The valve mechanism 158, as shown in Fig. 12, includes a conventional spool type slide valve 163 having its stem 164 pivotally connected to a link 165, to a lever 166 pivotally mounted on a pivot shaft 167 carried by the lower boring head frame and which in turn carries a suitable counterweight 168. A lever 169, also pivotally mounted on the shaft 167 to swing relative to the lever 166, has one of its arms 169^a provided with spaced lugs 170 and 171, and the other lever arm 169^b is pivotally connected at 172 to the lower end of an upright shifter rod 173. This rod extends axially within and is adjustably secured to a sleeve or tube 174 which extends upwardly through an opening 175 in the lower wall of the cutter frame 124. This tube has a flange 176 at its upper end and the tube passes through an opening in a plate 177 secured to the lower surface of the cutter frame and engaging this plate is an adjustable collar 178 clamped to the tube 174. Thus, the upper tube flange 176 and the tube-collar 178 provide spaced abutments engageable by the cutter frame as the latter is moved up and down to effect shifting of the automatic slide valve thereby to control the reverse movements of the elevating jacks for the cutter frame. The lever 169 has gear teeth on its hub which mesh with gear teeth on a lever 180 pivoted at 181 on the lower head frame, and a spring 182 is connected between the outer end of this lever and the outer end of a lever arm 169^c formed integral with the lever 169. Thus, as the lever 169 is swung back and forth the lever 180 and the spring 182 provide a quick-operating, snap action device so that the lever 169 may be quickly thrown as its passes center in one direction or the other, thus eliminating the possibility of dead centering of the mechanism. The tube 174 is adjustably secured to the rod 173 by a split clamp 184 which may be contracted by a wedge-like nut 185 to effect gripping of the rod 173. Thus, the tube may be adjusted axially relative to the rod and the collar 178 may be adjusted axially relative to the tube to vary the distance apart of the flange 176 and the collar 178, thereby to permit variation of the time of shifting of the automatic valve mechanism. The adjustable upper flange 176 serves to regulate the upper limit of movement of the upper cutter frame so as to accommodate the head mechanism to coal seams or mine veins of varying heights; while the adjustable collar 178 serves to regulate the operating range or amplitude of up and down movement of the cutter frame. Thus the cutter frame may have different predetermined operating movements in a vertical direction as the cutter chain circulates in its orbital path along the frame guideway.

The hydraulic fluid system associated with the various other hydraulic jacks of the apparatus above described, may be essentially similar to that disclosed in my application, Serial Number 191,004, mentioned above, and therefore a description thereof is herein unnecessary.

The rear conveying mechanism 12 may assume any conventional form and herein may be generally similar to

that disclosed in the copending Russell and Sibley applications, Serial Numbers 102,995 and 102,996, both filed on July 5, 1949. In this instance, the conveying mechanism 12 has a frame 190 along which an endless flight conveyor is guided for orbital circulation and as shown in Fig. 7, the forward portion of this conveyor underlies the rearward portion of the front conveying means 9 in such manner that the latter may discharge thereon irrespective of the longitudinal position of the support 3 and the disintegrating head mechanism 4 relative to the frame structure 2 during the forward sumping and retracting movements of the head. The conveyor frame 190 is pivoted at 191 to tilt in a vertical direction and the tiltable frame portion is also pivoted at 192, on an axis substantially coincident with the frame pivot axis 18, to swing laterally. Thus, the front conveying means 9 and the rearward conveying means 12 may be independently swung horizontally about a substantially common upright axis relative to the base. Hydraulic jacks 193 are provided for tilting the rearward frame portion of the conveying means 12 and conventional hydraulic jacks 194 pivotally mounted at 195 on the forward portion of the conveyor frame are provided for swinging the rearward conveyor frame portion laterally in manners fully disclosed in the Russell and Sibley applications above referred to.

The general mode of operation of the improved mining and loading apparatus is as follows: The apparatus may be trammed about the mine and positioned with respect to the working face of the mine vein by the crawler treads 17 of the mobile crawler base and when the apparatus is properly positioned with respect to the working face, as shown in Fig. 15, the treads may be suitably locked to hold the base stationary. The hydraulic jacks 23 may then be operated to effect swinging of the tiltable support 3 downwardly about its pivot 22 to bring the nose 50 of the disintegrating head mechanism 4 down to the floor level. As the boring instruments 54 revolve and the loop cutter chain 122 is orbitally circulated, the feed jacks 136 may be operated to move the support 3 together with the head mechanism forwardly along the guideways of the frame structure 2 to sump the disintegrating head mechanism into the material of the mine vein to the lateral position indicated in full lines at A in Fig. 14. As the disintegrating head mechanism is advanced the transverse penetrating edge of the front nose 50 serves to level the floor, breaking off the points P of mineral left on the floor by the series of overlapping bores formed by the boring instruments, as shown in Fig. 16. As the disintegrating head mechanism is thrust into the mine vein, the four rotary boring instruments form a series of overlapping bores designated B, in Fig. 16, while the upper loop cutter chain forms an elongated opening O extending transversely above the tops of and communicating with the bores B. Thus, a relatively large cut generally rectangular in outline is formed in the vein. As the mineral is dislodged from the solid vein and is disintegrated, it falls downwardly and passes rearwardly through the front openings 96, 97 and 98 into the zone of accumulation within the head. The disintegrated mineral may pass rearwardly through the central opening 96 directly onto the front receiving portion of the conveying means 9 while the rotary gatherers 7 gather the loose mineral from the floor at the sides of the head and move it rearwardly through the side openings 97 and 98 into the large chambers 101 where it is engaged by the rotary conveyor devices or impellers 8 and moved laterally onto the conveying means 9. As the disintegrating head mechanism is advanced as mining progresses, the support 3 may be tilted by the jacks 23 to vary the elevation of the lower disintegrating portion 5 and the upper disintegrating portion 6 may be adjusted in a vertical direction by the jacks 123 to enable the disintegrating head mechanism readily to follow a rolling seam or vein, and in the event the height of the mine vein varies, the upper

disintegrating portion 6 may be readily moved up and down to the desired elevation. When this lateral cut has been completed the head mechanism may be retracted by the feed jacks 136 and the swing jacks 24 may then be operated to swing the frame structure 2 horizontally about its pivot 18 to the opposite side of the base to bring the head mechanism into the angularly disposed position shown in dotted lines at C in Fig. 14. The head mechanism may then again be sumped into the mine vein to the position indicated at D in Fig. 14, and thereafter the head mechanism may be swung horizontally to its position centrally of the base as indicated at E in Fig. 15, and the sumping operation may again be repeated, as indicated at F in Fig. 14, thereby to complete the disintegration of a wide section of mineral extending completely across the face. The base of the apparatus may then be operated to propel the apparatus forwardly to a new disintegrating position with respect to the mine vein and the operations above described may be repeated. Evidently, by properly positioning the apparatus by the crawler treads and by swinging the frame structure 2 laterally with respect to the base, the head of the apparatus may be turned relatively sharply to cut along a curved path either to the right or left as desired.

It is desirable to make the two lateral cuts first and the central cut last, as above described, to balance the disintegrating loads on the head mechanism and to improve floor clean-up. Evidently, if desired the head mechanism during the disintegration of a relatively high vein may be first tilted up to operate at a high level near the roof, and thereafter may be tilted down to operate at a lower level near the floor, thereby completely to disintegrate the mineral of the high vein in a manner known as shelf cutting. Obviously the tiltable mounting for the head mechanism and the adjustable upper cutter frame enables the apparatus to meet a wide range of operating conditions. It will further be noted that normally the upper cutter frame is adjusted to the roof level while the lower boring head portion is positioned at the floor level, and such adjustment is maintained during the dislodging operation, and the entire head is tilted up and down by the hydraulic jacks 23, so as to enable the head to follow a rolling or uneven bottom. Also, if desired, the crawler treads of the crawler base may be employed to sump in the head during the central cut. The travel of the feed pistons of the feeding jacks 136 is desirably greater than the normal sumping feed so that the head mechanism, upon completion of a cut, may be retracted a substantial distance from the working face, as shown in Fig. 15, thereby to provide the necessary clearance between the head and face during lateral adjusting movements of the head. Such clearance is also desirable since some disintegrated mineral remains on the floor near to the face which might impede proper lateral adjustments of the head.

As a result of this invention an improved mining and loading apparatus is provided whereby the face of a mine vein may be rapidly disintegrated and loaded out with the need of but a few repositioning movements of the apparatus thereby to effect substantially uninterrupted mining and loading of the mineral. By the provision of the novel adjustable mounting structure for the upper and lower disintegrating portions of the disintegrating head mechanism, the apparatus may readily follow a rolling or uneven mine vein or coal seam and may readily be adjusted to accommodate itself to mine veins of widely varying heights. The novel disintegrating head structure embodying the large flow openings for the disintegrated mineral, together with the large zone of accumulation of the disintegrated mineral within the head, the rotary gatherers, the novel disposition of the conveying means within the head, and the rotary conveyor devices within the head, enable the disintegrated mineral to flow relatively freely toward the conveying means thereby substantially to reduce the possibility of clogging and en-

abling a substantial increase in the production of large lumps. The apparatus is not only readily vertically adjustable but also has a relatively wide range of lateral adjustment, thus, affording a flexibility in operation 5 highly desirable to meet a wide range of mining conditions. By the provision of the laterally swingable boring and cutter head mechanism and the mobile base, the apparatus may readily travel along sharply curved paths such as are frequently encountered in an underground coal mine. By the provision of the narrow conveying means together with the large capacity flow of disintegrated mineral to the conveying means, greater flexibility is provided, as well as a substantial increase in the overall efficiency of the apparatus. The apparatus is not only 10 extremely flexible and efficient in operation but is also relatively simple and rugged in design. These and other advantages of the invention will be clearly apparent to those skilled in the art.

While there is in this application specifically described 15 one form which the invention may assume in practice, it will be understood that this form of the same is shown for purposes of illustration and that the invention may be modified and embodied in various other forms without departing from its spirit or the scope of the appended 20 claims.

What I claim as new and desire to secure by Letters 25 Patent is:

1. In a mining apparatus, the combination comprising a mobile base, a frame structure swivelly mounted at the rear end of said base to swing horizontally relative thereto into positions wherein the outer portion of said frame structure overhangs the sides of said base, an elongated centrally located support pivotally mounted at its rearward portion on said swingable frame structure for tilting movement relative thereto, a mine vein disintegrating head mechanism carried at the outer end of said tiltable support in advance of said outer portion of said swingable frame structure and embodying a lower disintegrating head portion extending transversely the full width of said frame structure and a cooperating relatively adjustable upper disintegrating head portion, said head portions cooperating to form an opening in a solid mine vein of such dimensions as to receive said outer portion of said frame structure and said outer end of said support, and means for mounting said tiltable support on said frame structure for rectilinear guided movement back and forth relative thereto whereby said disintegrating head mechanism may be summed forwardly into the mineral of the vein or may be retracted from the vein.
2. A mining apparatus of the character set forth in claim 1 wherein motor operated mechanism is mounted on said frame structure for driving said upper and lower disintegrating head portions of said disintegrating head mechanism, and power operated means is provided for varying the elevation of said upper disintegrating head portion relative to said lower head portion.
3. A mining apparatus as set forth in claim 2 wherein means is provided which is actuated by the movement of said upper disintegrating head portion for automatically controlling the operation of said power operated means whereby said upper head portion may be continuously moved up and down relative to said lower portion during the disintegrating operation.
4. A mining apparatus as set forth in claim 2 wherein said lower disintegrating head portion comprises a series of coating boring instruments arranged side by side in a common transverse zone on parallel longitudinal axes.
5. A mining apparatus as set forth in claim 2 wherein said upper disintegrating head portion comprises a guide frame providing a guideway and an endless face type chain cutter is guided for orbital circulation along said guideway of said guide frame, said chain cutter having cutting elements projecting from its forward side whereby 70 when said upper head portion is moved up and down the

mineral acted on by said cutting elements is dislodged and disintegrated.

6. A mining apparatus of the character set forth in claim 1 wherein said lower disintegrating head portion is formed with a transverse space for receiving the lower portion of said upper head portion when the latter is in its lowered position.

7. A mining apparatus as set forth in claim 4 wherein said lower disintegrating head portion has a transverse space located rearwardly of said rotary boring instruments for receiving the lower portion of said upper disintegrating head portion when the latter is in lowered position.

8. In a mining apparatus, a disintegrating head mechanism for disintegrating the mineral of a solid mine vein to form an opening in the mine vein of such dimensions as to receive the apparatus as mining progresses, said disintegrating head mechanism comprising, in combination, a lower disintegrating head portion for completely disintegrating the lower portion of the vein and a cooperating adjustable upper disintegrating head portion for disintegrating the upper portion of the vein near the roof level, said head portions both having movable disintegrating elements and cooperating to form said opening, motor operated mechanism for concurrently driving said disintegrating elements of both of said head portions, and power operated means for continuously moving said upper head portion up and down relative to said lower head portion during the disintegrating operation completely to disintegrate said upper portion of the mine vein.

9. A mining apparatus as set forth in claim 8 wherein power operated means is provided for thrusting said disintegrating head mechanism forwardly into the mineral of the mine vein while said upper head portion continuously moves up and down relative to said lower head portion to effect complete disintegration of the mineral at said upper portion of the mine vein as aforesaid.

10. A mining apparatus as set forth in claim 8 wherein means is provided embodying a shiftable control device which is actuated by the up and down movements of said upper head portion for automatically controlling said power operated means whereby said upper head portion is continuously moved up and down relative to said lower portion during the disintegrating operation.

11. A mining apparatus as set forth in claim 8 wherein said lower head portion comprises a series of coacting rotary boring instruments arranged side by side in parallel overlapping relation and cooperating completely to disintegrate said lower portion of the mine vein as aforesaid.

12. A mining apparatus as set forth in claim 8 wherein said upper head portion comprises an endless chain type face cutter guided for orbital circulation in upright planes and carrying forwardly projecting disintegrating elements for completely disintegrating the mineral of the solid mine vein as said upper head portion is moved up and down as aforesaid, said endless cutter chain having parallel superimposed runs traveling in relatively opposite directions.

13. In a mining and loading apparatus, a disintegrating head mechanism comprising in combination a lower head frame, a series of coacting rotary boring instruments mounted on said head frame in parallel overlapping relation, said head frame carrying bearing supports in which said boring instruments are journaled, said head frame having a series of openings therein located beneath said bearing supports between the axes of rotation of said boring instruments comprising a central opening and a pair of side openings, said head frame having chambers therein rearwardly of said side openings to provide a zone of accumulation for the disintegrated mineral within said head frame, a centrally located conveying means extending into said zone of accumulation within said head frame with its forward receiving portion extending into

5 said central opening, the disintegrated mineral flowing through said side openings into said chambers, and conveying means within said chambers rearwardly of said side openings for engaging the disintegrated mineral in said zone of accumulation and for moving such mineral laterally onto said centrally located conveying means.

14. A mining and loading apparatus as set forth in claim 13 wherein said last mentioned conveying means for moving the mineral laterally as aforesaid comprises a pair of cooperating rotary conveyor devices arranged in said chambers and journaled on longitudinal parallel axes at the opposite sides of said centrally located conveying means with the latter located intermediate said axes of said rotary conveyor devices.

15. A mining and loading apparatus as set forth in claim 13 wherein a pair of cooperating rotary gatherers are arranged on horizontal transverse axes in said side openings at the opposite sides of said forward receiving portion of said centrally located conveying means for gathering disintegrated mineral on the floor and for moving such mineral rearwardly through said side openings into said chambers.

16. In a mining and loading apparatus, the combination comprising a mobile base, a horizontal frame structure swivelly mounted on said base to swing horizontally relative thereto, an elongated centrally located support pivotally mounted on said frame structure to tilt in a vertical direction relative thereto, a mine vein disintegrating head mechanism carried at the outer portion of said tiltable support in advance of said base and comprising a lower disintegrating head portion and a cooperating relatively adjustable upper disintegrating head portion, motor operated mechanism on said supporting structure for concurrently driving said upper and lower head portions, and means for moving said support back and forth longitudinally relative to said frame structure for sumping said head mechanism into the mineral of a solid mine vein and for retracting said head mechanism from the vein.

17. A mining and loading apparatus as set forth in claim 16 wherein said motor operated mechanism comprises motors mounted at the opposite sides of said frame structure, driving connections are provided between one of said motors and said lower disintegrating head portion, and driving connections are provided between said other motor and said upper head portion.

18. A mining and loading apparatus as set forth in claim 17 wherein said driving connections are extensible whereby said head portions may be continuously driven irrespective of the position of said head mechanism longitudinally back and forth relative to said frame structure.

19. In a mining apparatus, a disintegrating head mechanism for disintegrating the mineral of a solid mine vein to form an opening in the mine vein of such dimensions as to receive the apparatus as mining progresses, said disintegrating head mechanism comprising, in combination, a head frame, a series of four coacting rotary boring instruments mounted in parallel overlapping relation on said frame, each of said boring instruments having a coaxial drive shaft, a motor, driving connections between said motor and said coaxial drive shafts including a transverse shaft operatively connected directly to the two outer coaxial drive shafts, and driving connections between said two outer coaxial shafts and the two inner coaxial drive shafts respectively whereby the two inner boring instruments are driven by said two outer coaxial drive shafts respectively wholly independently of each other.

20. In a mining and loading apparatus, a disintegrating head mechanism for disintegrating the mineral of a solid mine vein to form an opening in the mine vein of such dimensions as to receive the apparatus as mining progresses, said disintegrating head mechanism comprising, in combination, a head frame, a series of four coacting rotary boring instruments mounted in parallel overlapping relation on said frame, each of said boring in-

struments having a coaxial drive shaft, a motor, driving connections between said motor and said four coaxial drive shafts including a transverse shaft operatively connected directly to the two outer coaxial drive shafts, and driving connections between said two outer coaxial shafts and the two inner coaxial drive shafts respectively whereby the two inner boring instruments are driven by said two outer coaxial drive shafts respectively wholly independently of each other, rotary conveyor devices arranged on parallel axes parallel with the axes of said four drive shafts, and driving connections between said two outer coaxial drive shafts respectively and said conveyor devices.

21. In a mining and loading apparatus, a disintegrating head mechanism comprising, in combination, a head frame, a series of coating rotary boring instruments arranged in overlapping relation on parallel longitudinal axes, bearing supports carried by said head frame in which said boring instruments are journaled, said head frame having a series of openings below said bearing supports comprising a central opening and a pair of side openings, a conveyor extending longitudinally into said head frame with its forward receiving portion lying within said central opening, and gathering and conveying means within said head frame for gathering loose mineral on the floor and for moving such mineral rearwardly through said side openings and laterally onto said conveyor.

22. A mining and loading apparatus as set forth in claim 21 wherein said gathering and conveying means comprises a pair of rotary conveyor devices journaled within said head frame on longitudinal axes at the opposite sides of said conveyor, said conveyor devices engaging the disintegrated mineral moved rearwardly through said side openings and moving the same laterally onto said conveyor as aforesaid.

23. A mining and loading apparatus as set forth in claim 21 wherein said gathering and conveying means comprises a pair of rotary gatherers arranged on aligned transverse axes within said side openings for moving the disintegrated mineral rearwardly through said side openings.

24. In a mining and loading apparatus, a mine vein disintegrating head mechanism comprising, in combination, a head frame, a centrally located conveyor extending forwardly into said head frame, a series of four coating rotary boring instruments mounted on said head frame on parallel longitudinal axes, said conveyor having its forward receiving portion located intermediate the two inner parallel axes, chambers arranged in said head frame at the opposite sides of said conveyor for receiving mineral disintegrated by said boring instruments, and rotary conveyor devices arranged in said chambers for engaging the disintegrated mineral therein and for moving such mineral laterally onto said conveyor over the sides of the latter.

25. In a mining and loading apparatus, the combination comprising a mobile base, a horizontal frame structure swivelly mounted at its rearward portion at the rear end of said base to swing horizontally relative thereto into positions wherein the forward portion of said frame structure projects beyond the sides of said base and in advance of the latter, an elongated intermediate frame pivotally mounted at its rear end on the rearward portion of said frame structure to tilt in a vertical direction relative thereto and projecting in advance of said frame structure, a mine vein disintegrating head mechanism carried at the forward end of said tiltable frame for disintegrating the mineral of a solid mine vein, said mechanism having a head frame which is interiorly open to provide a chamber for receiving the disintegrated mineral discharged from said head mechanism, and conveying means on said tiltable frame and extending forwardly and downwardly with its forward receiving portion disposed within said chamber provided by the interior opening of said head mechanism for receiving the disintegrated mineral

discharged into said chamber and for conveying such mineral in said chamber rearwardly away from said head mechanism.

26. A mining and loading apparatus as set forth in claim 25 wherein longitudinal guiding means is provided by said supporting structure for guiding said tiltable frame for back and forth movement longitudinally relative to said frame structure thereby to effect forward sumping and retracting movements of said head mechanism.

27. A mining and loading apparatus as set forth in claim 25 wherein a rearward conveyor is provided on said frame structure for receiving the disintegrated mineral discharged from said front conveying means and means is provided for swivelly mounting said rearward conveyor to swing horizontally about an axis substantially coincident with the axis of horizontal swing of said frame structure relative to said base.

28. In a mining and loading apparatus as set forth in claim 8 wherein the disintegrating elements of both head portions are orbitally movable.

29. In a mining apparatus, the combination comprising a mobile base, a horizontal frame structure swivelly mounted on said base to swing horizontally relative thereto, a supporting structure adjustably mounted on said swingable frame structure for movement in a vertical direction relative thereto, a mine vein disintegrating head mechanism carried at the outer portion of said adjustable supporting structure in advance of said base and adapted to disintegrate the mineral of a solid mine vein, said head mechanism comprising a lower disintegrating head portion and a cooperating relatively adjustable upper disintegrating head portion, motor operated means for swinging said frame structure and for adjusting said supporting structure to vary the operating position of said head mechanism with respect to the face of the mine vein, motor operated means for concurrently driving said upper and lower head portions, and means for moving said adjustable supporting structure back and forth relative to said swingable frame structure for sumping said head mechanism into the mineral of the mine vein and for retracting said head mechanism from the vein.

30. In a mining apparatus, a mine vein disintegrating head mechanism for disintegrating the mineral of a solid mine vein to form an opening in the mine vein of sufficient dimensions to receive the apparatus as mining progresses and comprising a relatively wide lower head portion for completely disintegrating the mineral at the lower portion of the mine vein in planes at and above the floor level and a cooperating relatively adjustable upper disintegrating head portions movable up and down relative to said lower head portion for completely disintegrating the mineral at the upper portion of the mine vein in planes at and below the roof level, said head portion cooperating to form a cut of substantial width extending the full height of the mine vein between the floor and roof, and continuously operating motor operated mechanism connected between said head portions for automatically continuously moving said upper head portion up and down relative to said lower head portion.

31. A mining apparatus as set forth in claim 29 wherein in conveying means is provided for receiving the disintegrated mineral from said head mechanism and for conveying the same rearwardly of the apparatus, said conveying means having a rearward conveyor portion swingable horizontally about an axis substantially coincident with the axis of horizontal swing of said horizontal frame structure.

32. In a mining and loading apparatus, a disintegrating head mechanism comprising, in combination, a head frame, a series of coating rotary boring instruments arranged in side-by-side overlapping relation on parallel longitudinal axes, bearing supports carried by said head frame in which said boring instruments are journaled, said head frame having a series of openings below said

bearing supports comprising a central opening and a pair of side openings, conveying means extending longitudinally into said head frame between said side openings with its forward receiving portion lying within said central opening, and conveying means within said head frame for receiving loose mineral flowing rearwardly through said side openings and for moving such mineral laterally onto said first mentioned conveying means.

33. A mining and loading apparatus as set forth in claim 32 wherein said second mentioned conveying means comprises a pair of rotary conveyor devices journaled within said head frame at the opposite sides of said first mentioned conveying means.

34. A mining and loading apparatus as set forth in claim 32 wherein an upper disintegrating device cooperates with said series of coacting rotary boring instruments in the disintegration of the mineral and arranged at the roof level above said boring instruments, and said head openings also receiving the mineral disintegrated by said upper disintegrating device.

35. In a mining apparatus, the combination comprising a base, a frame structure mounted on said base, an elongated support pivotally mounted at its rearward portion on said frame structure for tilting movement in vertical planes relative thereto, a mine vein disintegrating head mechanism carried at the outer end of said tiltable support in advance of the outer portion of said frame structure and embodying a lower disintegrating head portion extending transversely the full width of the outer portion of said frame structure and a cooperating relatively adjustable upper disintegrating head portion extending transversely of said frame structure substantially the full width of the latter and operating in planes above said lower head portion, said lower and upper head portions operating when concurrently advanced into a solid mine vein to dislodge and disintegrate transverse superimposed sections of mineral from the vein and cooperating to form an opening in the mine vein of such dimensions as to receive said outer portion of said frame structure and said outer end of said support as mining progresses, and means for mounting said tiltable support on said frame structure for rectilinear guided movement back and forth longitudinally relative thereto concurrently to sump said upper and lower portions of said disintegrating head mechanism forwardly into the mineral of the vein or to retract said head mechanism from the vein.

36. A mining apparatus of the character set forth in claim 35 wherein motor operated mechanism is mounted on said frame structure for driving said upper and lower disintegrating head portions of said disintegrating head mechanism, and power operated means is provided for varying the elevation of said upper disintegrated head portion relative to said lower head portion to increase the height of the section of mineral dislodged and disintegrated by said upper head portion thereby to vary the height of the roof level of said opening.

37. In a mining apparatus, the combination comprising a base, a mine vein disintegrating head mechanism carried by said base and embodying a tiltable frame carrying a lower disintegrating head portion extending transversely the full width of said base and a second frame tiltably mounted on said first frame and carrying a cooperating upper disintegrating head portion extending transversely of said base substantially coextensively with said lower head portion and adjustable in vertical planes relative to said lower head portion, said lower and upper head portions operating when concurrently advanced into a solid mine vein to dislodge and disintegrate transverse superimposed sections of mineral from the vein and cooperating to form an opening in the mine vein of such dimensions as to receive said base as mining progresses, motor operated mechanism carried by said base for driving said upper and lower disintegrating head portions, power operated means for varying the elevation of said upper head portion relative to said lower head portion

5 to increase the height of the section of mineral dislodged by said upper head portion thereby to vary the height of the roof level of said opening, and means for concurrently advancing said upper and lower head portions into the mineral of the mine vein.

38. A mining apparatus as set forth in claim 37 wherein said lower disintegrating head portion carried by said first tiltable frame comprises coacting boring instruments arranged side by side in a common transverse zone on parallel axes extending longitudinally of said tiltable frame.

39. In a mining apparatus, the combination comprising a base, a mine vein disintegrating head mechanism carried by said base and embodying a tiltable frame carrying a lower disintegrating head portion extending transversely the full width of said base and a second frame tiltably mounted on said first frame and carrying a cooperating upper disintegrating head portion adjustable in vertical planes relative to said lower head portion, said upper disintegrating head portion comprising a guide frame providing a guideway and an endless face type, loop chain cutter guided for orbital circulation along said frame guideway and having parallel superimposed runs traveling in relatively opposite directions, said loop chain cutter having cutting elements projecting from its forward side whereby when said upper head portion is moved up and down the mineral acted on by said cutting elements is dislodged and disintegrated, said lower and upper head portions cooperating to form an opening in a solid mine vein of such dimensions as to receive said base as the apparatus is advanced, motor operated mechanism carried by said base for driving said upper and lower disintegrating head portions, and power operated means for varying the elevation of said upper head portion relative to said lower head portion thereby to vary the height of the roof level of said opening.

40. A mining apparatus as set forth in claim 37 wherein said tiltable frame of said upper disintegrating head portion is pivotally mounted at its rearward portion with its pivot located a substantial distance rearwardly of said lower head portion and above said base, said upper head portion comprising orbitally moving cutting elements which are carried at the forward portion of said second tiltable frame for dislodging and disintegrating a transverse section of mineral in planes above the top of said lower head portion, and said power operated means for varying the elevation of said upper head portion embodies a power device for tilting said second frame.

41. In a mining apparatus, a mine vein disintegrating head mechanism for disintegrating the mineral of a solid mine vein and comprising a relatively wide lower head portion for disintegrating the mineral at the lower portion of a mine vein, said lower head portion comprising coacting rotary boring instruments mounted to revolve on parallel longitudinal axes to form parallel overlapping bores in the mine vein, said head mechanism also including a cooperating relatively adjustable upper disintegrating head portion extending in horizontal planes transversely of the upper portions of said boring instruments substantially coextensively with said lower head portion and tiltably up and down relative to said lower head portion for dislodging and disintegrating a transverse section of mineral at the upper portion of the mine vein, the axis of tilt of said upper head portion being located a substantial distance rearwardly of said lower head portion so that said upper head portion swings through a wide arc as said upper head portion is tilted, said upper and lower head portions concurrently operating to form a cut of substantial width extending the full height of the mine vein between the floor and the roof, motor operated mechanism for tilting said upper head portion up and down about its pivotal axis relative to said lower head portion to vary the height of the cut, and means for concurrently advancing said upper and lower head portions into the mineral of the mine vein.

42. A mining apparatus as set forth in claim 41 wherein in said lower head portion is mounted for adjustment in vertical planes to vary its elevation with respect to the mine floor and said adjustable upper head portion is mounted for adjustment in vertical planes in unison with said lower head portion.

43. In a mining apparatus, the combination comprising coacting rotary boring instruments arranged in overlapping relation on parallel longitudinal axes for forming parallel overlapping bores in a solid mine vein between the roof and floor, orbitally moving cutter means having a horizontal portion extending substantially in parallelism with a horizontal line tangential to the tops of the circular paths of said rotary boring instruments and a parallel portion at a higher elevation, said parallel portions cooperating to remove a transverse section of mineral from the mine vein to provide an elongated recess in the mine vein near the roof level in planes above said overlapping bores with said recess in communication with the latter; and means for adjusting said cutter means in upright planes relative to said boring instruments to vary the height of the section of mineral removed thereby.

44. A mining apparatus as set forth in claim 43 wherein said cutter means is in the form of an endless loop cutter chain and said cooperating parallel portions of said cutting means are constituted by the bottom and top runs of said cutter chain.

45. A mining apparatus as set forth in claim 43 wherein means is provided for adjusting the elevation of said rotary boring instruments, and said cutter means is mounted for adjustment in unison with said boring instruments.

46. A mining apparatus comprising, in combination, a mine vein disintegrating head mechanism for cutting out an opening in a solid mine vein between the floor and roof and comprising a lower disintegrating head portion and a cooperating relatively adjustable upper disintegrating head portion, said upper head portion extending transversely of said lower head portion and said portions operable when advanced to remove superimposed transverse sections of mineral from the mine vein, and means for mounting said upper head portion for tilting adjustment up and down relative to said lower head portion to vary the height of the transverse section of mineral removed by said upper head portion thereby to vary the height of the opening in the mine vein, said upper head portion when in raised position having its bottom disposed in proximity to a horizontal plane lying at the top of said lower head portion, said upper head portion when in lowered position having its lower portion disposed rearwardly of and overlapping with said lower head portion, said lower head portion having a transverse space located rearwardly thereof for receiving the lower portion of said upper head portion.

47. In a mining apparatus, a disintegrating head mechanism for disintegrating the mineral of a solid mine vein comprising, in combination, a lower disintegrating head portion and a cooperating adjustable upper disintegrating head portion, said head portions both having movable disintegrating elements, motor operated mechanism for concurrently driving said disintegrating elements of both of said head portions, and power operated means for continuously moving said upper head portion up and down relative to said lower head portion during the disintegrating operation, said power operated means including means embodying a power actuated oscillating element operatively connected to said upper head portion and means for oscillating said element to cause said up and down movement of said upper head portion.

48. A mining apparatus as set forth in claim 47 wherein adjustable means is provided for varying the range of oscillation of said oscillatory element thereby to vary the range of up and down movement of said upper head portion.

49. In combination, a frame structure movable over the floor of a mine, a dislodging and disintegrating head mechanism carried at the forward portion of said frame structure for dislodging and disintegrating the mineral of a solid mine vein, said frame structure providing chambers into which the dislodged and disintegrating mineral is discharged from said head mechanism, said chambers opening forwardly toward the forward portion of said head mechanism near the floor level, a conveying means extending centrally lengthwise of said frame structure between said chambers near the lower portions of the latter, conveyor devices on said frame structure rearwardly of said dislodging and disintegrating head mechanism and located within the longitudinal projection of the outer boundaries of said head mechanism, said conveyor devices disposed in vertical planes extending transversely of said frame structure and movable relative to each other and to said frame structure during their operation, said chambers having closed outer sides and opening at their inner sides toward said conveying means, said conveyor devices acting on the mineral dislodged and discharged rearwardly by said head mechanism to move such mineral laterally toward and inwardly beyond the sides of said conveying means, and means for concurrently moving said conveyor devices as aforesaid to effect their conveying function.

50. A combination as set forth in claim 49 wherein said conveyor devices comprise rotary impellers disposed in said chambers on parallel axes extending longitudinally of said frame structure, one impeller at each side of said conveying means.

51. A combination as set forth in claim 50 wherein said dislodging and disintegrating head mechanism comprises rotary disintegrators disposed in said chambers on parallel axes extending longitudinally of said frame structure and said impellers are disposed with their axes of rotation in parallelism with lines parallel with the axes of said rotary disintegrators, said rotary impellers being centrally open for receiving the dislodged mineral discharged rearwardly from said rotary disintegrators.

52. A combination as set forth in claim 49 wherein said movement of said conveyor devices is a rotary movement.
